PERMANENT-WAVE APPARATUS.

Application filed July 20, 1927. Serial No. 207,247.

Our invention relates to hair curling or permanent wave apparatus as used to produce the so-called permanent waves in women's hair, and the objects of the invention are to provide apparatus which will be more effective than prior apparatus used for this purpose and which will tension the hair when winding the same on the waving spools without pulling at the scalp of the person whose hair is being treated, and which will produce a wave in the hair closer to the scalp than was formerly possible.

The drawings accompanying this application show one embodiment of our invention, tho it is to be understood that such changes as may be made within the scope of the invention are intended to be covered in the appended claims.

Fig. 1 is an approximately half size plan view of our apparatus showing the hair tensioned from adjacent the scalp to the winding spool. Fig. 2 is a side elevation of Fig. 1. Fig. 3 is an elevation of the opposite side to Fig. 2 showing the forward portion 25 of the apparatus only. Fig. 4 is an end view of Fig. 1. Fig. 5 is an end view of Fig. 2. Fig. 6 is a plan view of a winding spool shown approximately full size. Figs. 7 and 8 are respectively plan and edge views 30 of the special heat insulating clip used next to the scalp. Fig. 9 is an approximately full size plan view of the hair clamping member. Figs. 10 and 11 are respectively opposite sides of Fig. 9. Fig. 12 is a front 35 end view of Fig. 9. Fig. 13 is a cross section of the clamp as taken from the line 13-13 of Fig. 9 but shown with the U shaped electric heater in place. Fig. 14 is a plan view of the heater. Fig. 15 is a plan 40 view of the spindle of the hair winding spool.

Briefly described our invention comprises a long frame supporting a hair clamping device at one end adapted for clamping the hair near the scalp, and a winding spool upon which the hair is wound, and means for winding the hair on the spool under controllable tension without pulling at the scalp, also means for locking the wound 50 spool firmly against the clamp, means for releasing the clamp and spool from the tensioning frame, and an electric heater of special form which embraces both clamp and spool so as to heat the same to permanently 55 set a wave or curl in the hair, it being un-

derstood that the hair is previously treated with suitable solutions and/or enveloped in a moist cloth so as to steam the hair while wound under tension on the spool when the heat is applied.

In further detail the drawings show an elongated frame 1 which may be a simple rod tho here shown as made of two parallel guides. A handle 2 is provided at one end of the frame for holding it generally in a horizontal extension from the head of the person being operated on, the handle being held in one hand, or preferably tucked in back of a belt or into a pocket worn by the operator, so as to leave both hands free.

At the opposite or outer end the frame carries the hair clamp device 3 adapted to clamp a strand 4 of hair adjacent the scalp 5, the clamp being removably held in place between the arms of an open ended yoke 6 which is pivotally mounted at 7 to the frame 1 so as to project laterally thereof and permit the frame being moved on an arc from the pivot without forcing the edges of the clamp against the scalp 5 of the head being operated on.

From the clamp 3 the strand of hair extends to a winding spool 8 rotatably carried on a carriage or block 9 slidably mounted on the frame 1, so that as the hair is wound 85 upon the spool the block and spool will advance toward the outer end of the frame.

Suitable means is provided for resisting free advance of the block to thereby put a tension on the strand of hair being wound 90 upon the spool, and the means here shown is a cord 10 attached to the block and passing rearwardly to and over a spring actuated reel or drum 11 rotatably mounted on the rear end of the frame. The drum is 95 fitted inside with a spiral spring 12 tending to wind the cord upon the drum and thus pull the carriage block and hair spool backward with a given tension, or conversely to permit the spool to be advanced to the opposite end of the frame under this given tension in winding the hair thereon.

The tension produced by the spring in the rewinding reel is the minimum tension at which the apparatus will operate, but as 105 it is desirable to apply the maximum tension which the particular strand of hair will stand, brake means is provided for increasing the resistance of the drum to unwinding of the cord. This brake means comprises 110

a friction band 13 connected at one end at 14 to the frame, thence passing around the drum and connected at the other end to a pivoted thumb lever 15 normally held in released position by a small spring 16 and the lever so arranged that a slight pressure of the finger upon it will increase the resistance to rotation of the drum to any required degree.

- 10 It is of course evident that the resistance to travel of the carriage 9 may be placed on the carriage itself if desired, and under some circumstances such an arrangement will be more convenient to operate, or may 15 be operated in conjunction with the spring return drum. Such a resistance to carriage travel is shown in a brake 17 carried by the carriage and impinging the frame 1 to any desired degree upon turning the milled nut 20 18 so as to put any amount of frictional resistance to travel of the carriage or stop it altogether.

It is sufficient without further illustration to say that this carriage brake may have 25 resilient material for its shoe or resilient mounting of a rigid shoe in the common manner of obtaining sensitive even brake control.

The carriage brake is also useful in locking 30 the carriage against flying backward under influence of the spring return drum when releasing the spool from the carriage after winding the hair thereon, it being understood that a great many spools are 35 used and a strand of hair wound upon one after the other all over the head of the person being operated on.

The hair spool 8 best shown in Fig. 6 is 40 larger at each end and provided with a cleat 19 pivoted at one end at 19' so as to swing outward as indicated in dotted lines so that the strand of hair may be placed thereunder around the spool and held firmly in place by the cleat forced tightly upon it by successive layers of hair wound over it.

45 The enlarged ends of the spool are provided with ratchet gears taking the form of a series of holes or notches 20 for locking the spool against rotation when tightly rolled into place against the clamp device 3 50 as shown in Fig. 13, a spring pawl 21 mounted on the clamp device engaging the holes, and releasable with the finger.

To mount the spool on the carriage a loose 55 spindle 22 is provided which is passed through the spool and through a revoluble hub 23 on the carriage, and which hub is provided with a driving pin or jaw 24 engaging a groove in the end of the spool so 60 as to make both rotate together. A large milled head 25 on the outer end of the hub provides a finger gripping member whereby to wind the spool.

65 To prevent unwinding of the spool when changing the finger grip upon the milled

head, a ratchet wheel 26 is provided on the hub 23 adjacent the outer side of the frame cooperating with a spring actuated finger releasable pawl 27 mounted on the carriage.

The spool may be applied with either end 70 to the hub 23 and the spindle is provided with a groove 28 (see Fig. 15) frictionally held by a suitable spring detent 47 within the hub so that the spindle may be quickly inserted or withdrawn in applying and removing the successive spools.

75 The hair clamp device 3 is best shown in Figs. 9 to 14 and comprises an upper and a lower die section respectively designated 3 and 3' fitting into one another along a curved line 29 to clamp and form the first wave in the hair adjacent the scalp. Draw bars or screws 30, 30' are provided at the ends of the die sections each fitted with small wing nuts 31 so that the sections may 80 be tightly drawn together to firmly clamp a strand of hair between the curved meeting faces.

85 The upper die section 3 is preferably pivoted to the draw bars at 32, 32' so that one 90 of the bars may be swung outward from pivot 32' as indicated in Fig. 11 and the upper section swung upward as indicated by the dotted line X in Fig. 11 so as to open the dies for insertion of the hair. 95 Draw bar 30' is preferably retained by a pin 33 working in a hole in the bar, or some other suitable stop, against free outward swinging so that the sections will always remain together.

100 The clamp or die sections are provided with a layer of cork or other heat insulation on their forward faces at 34 so as to prevent burning the scalp when heated, and recourse is also had to an additional protection in the form of a soft rubber or cork clip 35 made of flat sections of the material meeting on the line 36, each mounted on the end of a coiled wire spring 37 so that the sections may be sprung apart and clipped over the 110 strand of hair between the scalp and the hair clamp device 3 in the space there shown in Fig. 1.

115 The hair clamp device 3 is formed with a concavely curved rear face at 38 adapted to receive and seat the spool 8 when tightly wound with hair and locked thereagainst by the pawl 21 as shown in Fig. 13. The upper section of the clamp device is hollow and both sections are perforated as indicated at 39 so that steam may readily pass from the hair on the spool into the hair clamped in the dies.

120 In order to heat the device we provide a special U shaped electric heater 40 (see Figs. 125 13 and 14) which embraces both the tightly wound hair spool 8 and the clamp device 3. This heater is fitted inside with suitable electric heating elements in the well known manner not specifically embraced in the 130

present application and therefore not shown in the drawings. The heater is preferably though not necessarily made in two sections pivoted at 41, one section provided with a short handle 42 from which the current wires 43 extend, and the other with a small finger piece 44 for pressure of the finger to open the sections like a spring clothes pin, the sections being urged to close by a small spring 45.

In operation of the apparatus, a strand of hair is firmly clamped between the jaws of the clamp device 3, the carriage is advanced to the required degree and locked by the 15 brake 17, the end of the hair strand is wrapped around the spool 3 and held by the cleat 19, the brake 17 released, the required degree of tension placed on the drum 11 by means of the drum brake 13, or proper resistance given the carriage by carriage brake 17, and the hair strand is wound on the spool under the tension thus produced until the spool meets and locks against the clamp device 3 through means of the pawl 21. The 25 carriage is then locked with the brake 17 and spindle 22 withdrawn from the spool, and the frame disengaged from the clamp device by sliding it therefrom. Heat insulator clip 35 is next applied to the strand of 30 hair close to the scalp, the electric heater is placed in position and the current turned on until the hair has been sufficiently baked into permanent wave form.

As previously stated, the hair before winding is suitably moistened, usually with alkaline aqueous liquids adapted to soften the hair, as practised in the art of permanent waving of women's hair, and before the heater is applied a moist piece of cloth or felt 35 is laid over the hair wound spool and adjacent parts of the clamp device, and also a piece of tinfoil or other steam proof material is laid over the outside of the cloth or felt, or both, so as to imprison the steam generated by the heater and make it permeate every hair wound and clamped in the assemblage of die and spool.

Such wrappings of moist cloth, felt, and foil have been omitted from the drawings, 50 as they form no part of the invention and would only tend to obscure the drawings, but suffice to say the wrappings would occupy the space 46 between the heater and the hair spool and clamp and which space is 55 shown on Fig. 13 of the drawings.

We claim:

1. Hair waving apparatus comprising a device adapted to clamp a strand of hair adjacent the scalp, a member upon which the hair is adapted to be wound, and means for tensioning the hair strand between said device and said member while winding the hair upon the member.

2. Hair waving apparatus comprising a device adapted to clamp a strand of hair

adjacent the scalp, a member upon which the hair is adapted to be wound, and means for tensioning the hair strand between said device and said member while winding the hair upon the member, and means for varying the amount of tension put upon the strand while winding.

3. Hair waving apparatus comprising a device adapted to clamp a strand of hair adjacent the scalp, a member upon which the strand is adapted to be wound, means for tensioning the hair strand between said device and said member while winding the hair upon the member, and means for locking said member to said device when the hair is wound upon the member.

4. Apparatus as specified in claim 3 plus means for heating both the member and said device.

5. Apparatus as specified in claim 3 plus means for heating the member comprising a U shaped electric heating element adapted to embrace said member.

6. Apparatus as specified in claim 3 plus means for heating the wound hair comprising a U shaped electric heater adapted to embrace said member and said device.

7. Hair waving apparatus comprising an elongated frame, a hair strand clamping device removably supported at one end of the frame, a sliding carriage supported on said frame, a member upon which the strand is adapted to be wound rotatably supported on said carriage, means for rotating the member, and means resisting the free sliding of the carriage.

8. Apparatus as specified in claim 7 plus said means resisting the free sliding of the carriage being adjustable to vary the resistance to sliding of the carriage.

9. Apparatus as specified in claim 7 wherein said means resisting the free sliding of the carriage comprises a spring, return reel mounted on the frame, and a flexible device extending from the carriage passing around said reel all arranged to resiliently pull the carriage away from said clamping device.

10. In a hair waving apparatus, a hair strand clamping device, a frame provided with means for removably engaging the device, and means for supporting a hair strand receiving spool on said frame for winding thereon the strand extending from said clamping device.

11. In a hair waving apparatus, a hair strand clamping device comprising a pair of forming die members adapted to receive the strand between them, and means for clamping said die members together.

12. Apparatus as specified in claim 11 plus heat insulating means adapted to be positioned between said device and the scalp from which the hair strand extends.

13. Apparatus as specified in claim 11

plus a hair strand receiving spool, and means for holding said spool locked against said clamping device.

14. Apparatus as specified in claim 11 plus said die members being hingedly connected together to open for insertion of said strand.

15. Apparatus as specified in claim 11 plus said die members being perforated for 10 passage of steam to a strand of hair clamped therebetween.

16. Apparatus as specified in claim 11 plus one of said die members being hollow and perforated for passage of steam to a 15 strand of hair clamped therebetween.

17. In a hair waving apparatus, an insulating clip comprising a pair of relatively thin blocks and a resilient wire hinge connecting the blocks together so as to resiliently hold them in edgewise abutting relation. 20

18. Hair waving apparatus comprising a tensioning frame, a hair strand clamping device at one end of the frame, a hair strand winding spool rotatably mounted on the frame and for bodily movement therealong, 25 means for rotating the spool, and releasable means for preventing reverse movement of said spool.
